UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

INKING MECHANISM FOR PRINTING MACHINERY.

992,475.

Specification of Letters Patent. Patented May 16, 1911.

Application filed June 2, 1910. Serial No. 564,615.

To all whom it may concern:

Be it known that I, HOWARD M. BARBER, a citizen of the United States, and resident of Stonington, in the county of New London and State of Connecticut, have invented a new and useful Improvement in Inking Mechanism for Printing Machinery, of which the following is a specification.

This invention relates to improvements in printing machinery and is more particularly directed to improvements in the inking mechanism therefor.

In inking mechanisms where the fountain roll is held stationary during the intervals between its intermittent rotary movements, there is a tendency on the part of the ink, especially where very heavy ink is used, to draw away from the fountain roll and thus interfere with the proper deposit of the ink upon the doctor roll. I have discovered that by imparting to the fountain roll a continuous movement with a slow movement in the intervals between the more rapid movements imparted to the fountain roll at the time the doctor roll is in engagement therewith, I am enabled to secure a uniform deposit of the ink upon the doctor roll, the continuous movement of the fountain roll preventing this drawing away of the ink as hereinabove stated.

The object of my invention is to provide mechanism for imparting this continuous slow movement and intermittent faster movement to the fountain roll, the mechanism being so arranged that the device for driving the roll continuously may be disconnected so as to permit the fountain roll to be driven intermittently with stops between its movements, or to disconnect the device for driving the fountain roll intermittently for permitting the continuous slow movement of the fountain roll. For instance, with certain qualities of ink it may be advisable to simply drive the fountain roll intermittently with stops between its movements, or it may be desirable where only a very light deposit of color is required, to drive the fountain roll continuously with a slow movement.

A further object is to provide means for lengthening or shortening the stops in the intermittent movement of the fountain roll.

This invention is shown as applied to a multi-color printing press.

A practical embodiment of my invention

is represented in the accompanying drawings in which,

Figure 1 represents in front elevation, with the intermediate portion broken away, so much of an inking mechanism and its operating parts as will give a clear understanding of my invention. Fig. 2 represents the same in top plan. Fig. 3 represents the mechanism in side elevation with portions of the supporting frame shown in connection therewith. Fig. 3^a is a detail view showing the pawl carrying lever with the means for imparting the intermittent movement swung to the limit of its rearward movement. Fig. 4 is a detail vertical section taken in the plane of the line A—A of Fig. 1, looking in the direction of the arrows. Fig. 5 is a detail longitudinal section through the device for clutching the fountain roll shaft to and releasing it from the continuous feed device, and Fig. 6 is a transverse section through the same.

A suitable frame 39 forms a support for the ink fountain 46. The fountain roll is denoted by 128 and its shaft by 176, which shaft is mounted in suitable half bearings in the ends of the ink fountain 46 and the caps 177,178.

Manually operated means for rotating the fountain roll 128, comprises a spur gear 179 fixed to the shaft 176, which spur gear is engaged by a pinion 180 fixed on a shaft 181 carrying a crank handle 182. A shaft 183 is mounted in suitable bearings in the side frame 39 in alignment with the fountain roll shaft 176, adjacent to one end thereof and a clutch member 184 is arranged to be moved into and out of interlocking engagement with the inner end of the shaft 183. This clutch member 184 has a roller clutch connection 185 at all times with a sleeve 186 keyed to the fountain roll shaft 176. This clutch member 184 has a sliding movement on the sleeve 186 sufficient to permit the clutch member 184 to be moved entirely out of interlocking connection with the end of the shaft 183 when so desired. A manually operated lever 187 is pivoted at 188 on the fountain frame 189, the inner end of which lever is provided with a shoe 190 located in a circumferential groove 191 in the clutch member 184. A spring 192 tends to push the lever 187 in a direction to disconnect the clutch member 184 from the shaft 183. A swinging latch 193 is arranged to drop into

position to hold the lever 187 against the tension of the spring 192 with the clutch member 184 in interlocking engagement with the shaft 183. The shaft 183 is provided at 5 its outer end with a gear 141 which meshes with a worm 140 fixed to a diagonal shaft 139 mounted in suitable upper and lower bearings 194*, 195*, on the frame 39. Rotatory movement is imparted to the shaft 139 10 from the shaft 113 through the gears 137, 138.

The step by step movement is imparted to the fountain roll 128 by the following device. A ratchet wheel 194 is fixed to the fountain 15 roll shaft 176. A pawl carrying lever 195 and a pawl operating lever 196 are keyed to the stud shaft 176*, the pawl 197 being pivoted to the lever 195 in position to travel along the ratchet wheel 194, when moved in 20 one direction and to interlock with the ratchet wheel and move it and thereby the fountain roll, when moved in the opposite direction. A stop 198 is arranged to limit the rearward movement of the pawl 197, 25 which stop 198 is adjustably secured to the frame 39 by a pin and slot engagement 199, 200, therewith, a clamp screw 201 having an engagement with the pin 199 for securing the stop 198 in its desired position. A spring 202 30 engages the frame 39 and the pawl operating lever 196, which spring tends to hold the pawl 197 at the limit of its rearward movement. A rocking arm 203 is loosely mounted upon the stud shaft 176* and the free end of 35 the arm 203 is connected to a crank disk 204 on the cam shaft 122 by a connecting rod 205. This connecting rod 205 is adjustably secured to the crank disk 204 by a pin and slot connection 206, 107, a nut 208 being provided for clamping the connecting rod 205 in 40 the desired position on the crank disk 204, so as to determine the throw of the arm 203. This arm 203 is arranged to engage a lug 209 on the lever 196, for moving the levers 195, 45 196, and thereby the pawl 197 during a greater or lesser portion of the downward movement of the arm 203, according to the position of the stop 198 and the adjustable connection of the rod 205 with the crank disk 50 204.

The doctor roll 54 may be alternately engaged with the ink transfer roll 58 and the fountain roll 128 by the following device. The doctor roll carrying lever comprises 55 arms 210 fixed to the shaft 211, in which arms the doctor roll is mounted. Other arms 212, 213 are fixed to the shaft 211 and are provided with studs or rollers 214, 215, arranged to be engaged by a cam 216 fixed on 60 the cam shaft 122. A suitable spring 217 is interposed between a fixed abutment 218 on the frame 39 and a collar 219 on the rod 220 connected to the free end of an arm 221 fixed to the shaft 211 for holding the stud or roller 65 214 in engagement with the cam 216.

In operation, if it is desired to drive the fountain roll continuously at a slow speed, the clutch member 184 is interlocked with the shaft 183 and the pawl 197 is thrown back out of engagement with its ratchet 70 wheel 194. If it is desired to drive the fountain roll intermittently with periods of rest between its movements, the pawl 197 is engaged with its ratchet wheel 194 and the clutch member 184 is disconnected from the 75 shaft 183. If it is desired to impart to the fountain roll a combination of a slow continuous movement with an intermittent higher movement, the clutch member 184 is interlocked with the shaft 183 and the pawl 80 197 is dropped into engagement with its ratchet wheel 194.

The roller clutch connection between the clutch member 184 and the sleeve 186 on the shaft 176, permits the shaft 176 to be moved 85 more rapidly than the movement of the shaft 183 at the periods of the intermittent higher movement.

The amount of each rapid movement imparted to the fountain roll may be provided for by adjusting the stop 198 so as to engage the pawl lever at any desired point in the upward movement of the rocking arm 203, the balance of the movement of the arm being of no effect on the pawl lever. The movement of this rocking arm 203 can also be adjusted by properly positioning the connecting rod 205 on the crank disk 204, as hereinbefore described. 95

It is evident that various changes might be 100 resorted to in the construction, form and arrangement of the several parts without departing from the spirit and scope of my invention; hence I do not wish to limit myself 105 strictly to the structure herein set forth, but 105

What I claim is:

1. A printing press inking mechanism including a fountain roll and means for rotating it continuously at different alternating speeds. 110
2. A printing press inking mechanism including a fountain roll and means for rotating it at a continuous speed and at an intermittent higher speed. 115
3. A printing press inking mechanism including a fountain roll, means for rotating it at a continuous speed and independent means for rotating the fountain roll intermittently at higher speeds. 120
4. A printing press inking mechanism including a fountain roll, means for rotating it at a continuous speed and means for rotating the fountain roll intermittently at a higher speed without disconnecting the means for continuously rotating the roll. 125
5. A printing press inking mechanism including a fountain roll, means for rotating it at a continuous speed, independent means for rotating the fountain roll intermittently at a higher speed without disconnecting the 130

- means for continuously rotating the roll, and manually operated means for connecting and disconnecting the fountain roll and the said means for continuously rotating the roll.
5. 6. A printing press inking mechanism including a fountain roll, means for rotating it at a continuous speed, independent means for rotating the fountain roll intermittently at a higher speed and means for connecting 10 the fountain roll to and disconnecting it from either one or both of said rotating means.
7. A printing press inking mechanism including a fountain roll, means for rotating it at a continuous speed, independent means for rotating the fountain roll intermittently at a higher speed and manually operated means for connecting the fountain roll to, and disconnecting it from the first named 20 means.
8. A printing press inking mechanism including a fountain roll, means for rotating it at a continuous speed, independent means for rotating the fountain roll intermittently 25 at a higher speed and means for adjusting the length of the intermittent movement steps.
9. A printing press inking mechanism including a fountain roll and its shaft and 30 means for rotating said shaft at a continuous speed comprising a constantly rotating shaft, a clutch member arranged to connect and disconnect the two shafts and a clutch connection between the clutch member and the 35 fountain roll shaft.
10. A printing press inking mechanism including a fountain roll and its shaft and means for rotating said shaft at a continuous speed comprising a constantly rotating shaft,
- a clutch member arranged to connect and disconnect the two shafts, a clutch connection between the clutch member and the fountain roll shaft and independent means including a pawl and ratchet for rotating said fountain roll shaft intermittently at a 40 higher speed.
11. A printing press inking mechanism including a fountain roll and its shaft, a continuously rotating shaft and a clutch connection between the two and independent means for rotating said fountain roll shaft intermittently at a higher speed without disconnecting the continuously rotating shaft. 45
12. A printing press inking mechanism including a fountain roll and its shaft, a continuously rotating shaft and a roller clutch connection between the two and independent means for rotating said fountain roll shaft intermittently at a higher speed without disconnecting the continuously rotating shaft. 50
13. A printing press inking mechanism including a fountain roll and its shaft, a continuously rotating shaft and a roller clutch connection between the two, and independent means for rotating said fountain roll shaft intermittently at a higher speed without disconnecting the continuously rotating shaft and manually operated means for connecting and disconnecting the fountain roll shaft and continuously rotating shaft. 55
- In testimony, that I claim the foregoing as my invention, I have signed my name in presence of two witnesses, this twenty-sixth day of May 1910.
